(57) **CLAIM**

The ornamental design for a shoe midsole periphery, as shown and described.

DESCRIPTION

FIG. 1 is a perspective view of a shoe midsole periphery in accordance with my new design.

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The even length broken lines shown in the drawings represent portions of the shoe midsole periphery and environment.

(Continued)

mental structure in the form of a shoe upper and outsole that form no part of the claimed design. The dash-dot-dash broken lines define the bounds of the claimed design and form no part thereof. The surfaces devoid of shading lines form no part of the claimed design.
